Application July 16, 1943, Serial No. 494,906

4 Claims. (Cl. 2—74)

This invention relates to improvements in garment construction and has particular relation to ladies' garments utilizing a placket formation as a part of the garment ensemble.

Garments for the female form are generally of the form-fitting type, thus facing the conditions set up by a smaller waistline dimensions between the bust and the hips; with a multi-piece garment this condition is readily met, but with the type known as a "one-piece" garment the lesser dimensions of the waistline prevent putting on or taking off of the garment, if the waistline zone has permanent form-fitting dimensions. As a result, garments of this type are generally made with a placket formation—generally located below one of the arm holes, with the placket generally capable of being expanded or opened out to provide a temporary dimension of the waistline zone sufficient to pass over the bust or hips—dependent upon which direction the garment is applied to or removed from the wearer—the formation being arranged to permit the placket to be closed and the parts secured when the garment is on the wearer, closing of the placket formation setting up the form-fitting characteristic within the waistline zone.

Various developments of placket formations have been utilized, with the more modern developments designed to provide a definite closed appearance, a favorite arrangement being to employ a "zipper" structure in connection with plaits or folds, together with other fastening means, the purpose being to permit such manipulations as to secure the enlarged dimensions when the formation is opened and to conceal as far as possible the presence of the placket during wearing of the garment. Many different ways of doing this have been contemplated and developed, but all are more or less complicated due to the fact that ready access to the zipper must be had and the fact that the zipper length has to be such that the entire zone between bust and hips must be capable of providing the variable dimensions. Attempts have been made to eliminate the use of the zipper structure by the substitution of other forms of fastening means, but the arrangements proposed have remained complicated by the required plaits and folds.

Among the objects of the invention is that of eliminating the zipper formation, and to substitute therefor an arrangement of separable fasteners so positioned as to provide the form-fitting result—with the placket opening concealed—when the fasteners are connected, and provide the result in simple and efficient manner; and to

permit equally efficient opening of the placket formation during the positioning of the garment on or removal from the wearer. Another object is to permit a limited yield effect or stretch within the waistline zone—in horizontal direction—to adjust the zone for a snug fit in presence of slight variations in the wearer's waist measure. Also, it is a further object to eliminate as far as possible the plait and fold characteristics—other than those provided by seams—generally present in this form of garment, and to provide an arrangement that is simple and efficient in service, durable in construction, and which can be produced at reasonably low cost.

15 To these and other ends, therefore, the nature of which will be made apparent as the invention is hereinafter disclosed in detail, said invention consists in the improved constructions and combinations of parts hereinafter fully disclosed, 20 illustrated in the accompanying drawings, and more particularly pointed out in the appended claims.

25 In the accompanying drawings, in which similar reference characters indicate similar parts in each of the views—

Figure 1 is an elevation of a portion of a garment, the view showing the outside of the portion below the arm-hole, with the placket formation closed.

30 Figure 2 is a similar view of the inner or opposite face of the portion shown in Figure 1.

Figure 3 is a sectional view taken on line 3—3 of Figure 1.

35 Figures 4 and 5 are fragmentary sectional views taken on lines 4—4 and 5—5 of Figure 2.

Figures 6 and 7 are sectional views taken on lines 6—6 and 7—7 of Figure 1.

40 Figure 8 is a fragmentary elevation of a portion of the rear panel and showing the opposite side of the triangular flap.

45 For the purpose of the description the front of the dress is referred to as the front panel 10, and the rear of the dress is referred to as the rear panel 11, with the arm-hole to which the sleeve is attached indicated as 12. Generally, the placket line extends downward from the vicinity of the nadir point of the arm-hole, the length of the placket—with respect to the front panel—generally varying from a straight line by being 50 cut with a very shallow V-shape, so that when the placket is closed, the form-fitting effect will tend to produce a straight line—the portion of the rear panel co-operating therewith extends approximately straight downward.

55 In the present invention, however, the placket

portion of the front panel is more or less reversed from that just referred to, in that the edge of the front panel is given a shallow inverted V-shape—considered on the basis of a vertical line—so that the edge of the front panel actually projects beyond such vertical line in the form of a front flap 10a which is an integral part of the panel. The front panel 10 and rear panel 11 are joined together in the vicinity of the bottom of flap 10a by stitching.

Within the placket zone, the rear panel 11 is internally provided with a triangular flap 11a. This flap has its longer side—the side at which the flap is stitched to the rear panel and therefore extending vertically in the assembly—cut on the bias, so that this flap has the warp and weft threads of the fabric weave each extending angular to the vertical, with the two other sides of the flap corresponding or extending normal to such warp and weft of the weave.

The arrangement thus far described, provides a union of the front and rear panels below the placket zone, with the latter open to the arm-hole. However, in practice, lines of stitching 13—about one inch in length—extend transversely across a line which presents a continuance of such flap-uniting line, and which extend into the upper and lower end zones of flaps 10a and 11a—as indicated in Figures 1 and 2—and limit the active length of the placket zone.

As will be understood, the closed placket will present flap 10a as overlying the rear panel, while flap 11a will underlie the front panel. To secure flap 11a in this position the free apex zone of the flap carries one of the members 14 of a snap-fastener, the complementary member 14a being secured to the inner side of the front panel; after the garment is placed on the wearer, this flap is secured in position by connecting the snap-fastener members, thus connecting the front and rear panels across the placket line, by bringing the waistline zone into its form-fitting relationship.

In producing the latter effect the particular formation of flap 11a presents an important function. As will be seen from Figures 2 and 8, the warp and weft threads of the weave—indicated by the hatching shown—extend angular to both the vertical and the horizontal. Due to the fact that the snap-fastener referred to is remote from both lines of stitching 13 and located on a line midway between them, any pulling effect provided from the arm-hole area will be exerted in the direction of length of one of these threads, while the weight of the garment below the placket will provide a drawing effect exerted in the direction of length of the other of these threads; since the length of the threads offers no material yielding effect and the flap is definitely anchored by the snap-fastening, there will be no material yielding vertically of the parts of the garment during service. However, since the bias line of flap 11a extends vertically, and such bias line presents one of the edges of the placket zone, there is the possibility of a yield horizontally, since the direction of pull will be exerted angularly to the direction of length of the warp and weft threads; the length of yield is somewhat limited, due to the fact that flap 10a is secured to the outer face of the rear panel, as presently explained, but there is a sufficient amount of yield to compensate for at least some of the service conditions, such as slight adjustment to variations in the waist measure of the wearer, etc.

After flap 11a has been fastened as above in-

dicated, thus placing this flap beneath the front panel, flap 10a is secured in position to overlie the rear panel; the securing may be had in any desired manner, a simple and preferred form being as follows: A snap-fastening member 15 is secured to the underside of the front panel at the point where, under prior practice, the apex of the shallow V-shape cut-away portion would lie—the complementary member 15a of the fastener 15 is carried by the rear panel at the intersection of a horizontal line through such apex and the vertical seam-line along which flap 11a is secured to the rear panel. As a result, when members 15 and 15a are snapped together the front panel 10 will have the form-fitting relation which had been previously obtained by such shallow V-shape configuration of the placket edge of the front panel, since the fastener brings the front panel to the same position as in the earlier type. Since, however, the front panel formation of the placket zone is changed to the inverted V-shape, the fastening of the snap-fastener leaves flap 10a unsecured and as of a pseudo-diamond-shape, and this is secured in position relative to the rear panel by a hook and eye fastening 16 at the free apex zone of the flap 10a, the hook being carried by the underside of the flap and the eye—which may be of the thread type—at the proper position on the outer face of the rear panel but with the eye then concealed by the flap.

By this arrangement, it is apparent that the placket will be held closed by the use of the two snap-fasteners and the hook and eye, all located on the horizontal line referred to with fastener 15, 15a directly connecting the two panels together, while fastener 14, 14a connects flap 11a to the underside of the front panel, and the hook and eye formation 16 connects flap 10a and the outer side of the rear panel. Hence, the two panels are secured together at three spaced-apart points all located on the same horizontal line, and all readily manipulated for either closing or opening the placket.

The seams employed are of the usual type used in tailoring—the material sections are made over-size and are then stitched together along the proper lines, after which the excess selvage portions—indicated as 17—are folded over onto the body of the panels or flaps; the seam thus tends to take on a thread-concealing characteristic. A number of advantages are present. For instance, flap 10a—which under prior practice is omitted, tends to give the closed garment a more ornamental appearance, in that the straight line effect is changed to an inverted V-shape; however, it also provides the functional effect of completely concealing the seam along which flap 11a is secured to the rear panel; in addition it provides for a third securing position between the panels although this third position appears only to provide for flap-fastening. In other words, positioned flap 10a conceals all visible evidence of the presence of a closed placket zone.

Flap 11a provides a second fastening point (14, 14a) between the front and rear panels, this point and the hook and eye being located on opposite sides of and spaced from the direct fastening (15, 15a) between the two panels, thus completing the three-point fastening of the two panels on the horizontal line which represents the waistline. In addition, however, the bias characteristic of flap 11a serves the additional important advantage of permitting the limited yield effect on the waistline with its ability to provide

slight adjustable compensation within the waistline zone.

In addition, these results are obtained practically free of folds or plaits so far as the placket zone is concerned, the assembly of the placket formation, presenting—other than the folded-over seam selvage portions—the characteristics of a two-ply characteristic within the waistline zone area which is defined on one side by the free edge of flap 10a (exposed) and on the other side by the free edges of flap 11a (concealed), and with the placket line (presented by the secured edge of flap 11a and which is concealed during wearing of the garment) indicative of the division line of the two panels within this two-ply zone, thus placing the panels as one of the plies and the respective flaps as the other ply; this division line of the panels is not visible during wearing of the garment since flap 10a is integral with the front panel and thus presents the appearance of being an integral part of the front panel instead of a flap.

It is apparent, of course, that although the assembly thus described is set forth as presenting the conditions of a form-fitting structure, the invention is not limited in this respect, since the position of fastener members 14a and 15 on the under face of the front panel, and the position of the thread eye of the fastening 16 on the outer face of the rear panel, can be varied so as to provide for any desired waistline zone characteristic of the garment, so that it is obvious that the garment can be provided in other styles, including garments suitable for maternity purposes.

While we have herein disclosed a preferred form of structure, it will be readily understood that changes or modifications therein may be found desirable or essential in meeting the exigencies of service or the desires of the wearer, and we therefore reserve the right to make any and all such changes or modifications therein as may be found desirable or essential insofar as the same may fall within the spirit and scope of the invention as expressed in the accompanying claims, when broadly construed.

What is claimed as new is:

1. In garment construction wherein the garment includes a placket formation extending across the waistline and positioned between the front and rear panels of the garment and with the placket line extending generally in the direction of the arm-hole of the garment, and in combination, a rear panel having a triangular flap secured thereto along the placket line and adapted to extend in underlying relation to and be removably secured to the front panel, a front panel having a flap of shallow inverted triangular

- V-shape formed integral therewith with the flap adapted to overlie the placket line of the rear panel and be removably secured to such rear panel a material distance beyond such line, said 5 front and rear panels respectively carrying the members of a separable fastening means with the rear panel member positioned at the intersection of the placket line with a horizontal line corresponding to the waistline and with the front panel member located on such horizontal line but remote from the free apex of the shallow inverted V-shaped flap, the free apices of the flaps being adapted to lie substantially on such horizontal line, the straight edges of the two triangular 10 flaps forming the base lines of the triangles opposite the fastening means normally being in a single line extending lengthwise of the garment, and individual means for detachably securing the respective flaps to the opposing panel with such 15 means located within such free apex zones, whereby the placket may be detachably closed with the placket line concealed by detachably connecting the panels at three spaced-apart points on the waistline.
2. Garment construction as in claim 1 characterized in that the intermediate separable fastening means is positioned on the base lines of the two triangular flaps with the other two fastening means positioned respectively at the apices 20 of the triangular flaps to produce form-fitting characteristics of the panels in the waistline zone when the fastening means members are in connected relation.
3. Garment construction as in claim 1 characterized in that the front and rear panels are 25 permanently connected by a pair of stitching lines extending transverse to and crossing the placket line with the respective stitching lines located within zones in the vicinity of the ends of the secured side of the triangular flap to thereby 30 determine the length-dimension limits of the placket formation opening in the direction of length of the placket line.
4. Garment construction as in claim 1 characterized in that the material of the triangular 35 flap secured to the rear panel has two of its three sides formed normal, one to the weave warp and the other to the weft threads of the material with the third side cut bias to the warp and weft 40 threads and with such bias-cut side presenting the zone in which the flap is secured to the placket line of the rear panel, whereby the assembly will permit slight horizontal stretch in the waistline 45 zone for snug adjustment under slight variations 50 in the wearer's waist measure.
